CLAIM

The ornamental design for a communications device, as shown and described.

DESCRIPTION

FIG. 1 is a front, top, right perspective view of a communications device, showing the new design;

FIG. 2 is a rear, bottom, right perspective view thereof;

FIG. 3 is a front elevation view thereof;

FIG. 4 is a rear elevation view thereof;

FIG. 5 is a left side view thereof;

FIG. 6 is a right side view thereof;

FIG. 7 is a top plan view thereof; and,

FIG. 8 is a bottom view thereof.

The broken lines depict portions of the communications device that form no part of the claimed design.

1 Claim, 6 Drawing Sheets(56)
